UNITED STATES PATENT OFFICE.

HERBERT M. FRIENDLY, OF PORTLAND, OREGON.

TELEPHONE SYSTEM.

Application filed December 16, 1921. Serial No. 522,842.

The present invention has for its broad objects the metering of telephone calls completed through telephone exchange systems.

The invention in the specific form chosen for the illustration herein contemplates a so-called two-wire common battery automatic telephone system as has been widely used, the present invention necessitating novel departures from equipments heretofore known, so far as I am aware, in attaining the new objects, while retaining certain operative functions which are known.

The present invention contemplates the following and other novel objects:

a. Means for metering the chargeable calls completed from a subscriber's line, taking into account variable initial charge values depending upon the hour at which the call is made, and also an additional charge thereto, depending upon the hour and the duration of the connection.

b. Means for metering an initial charge and also a charge depending upon the duration of the call and upon the destination of the call. That is to say, an initial charge and an additional different meter registration will be made to different destinations for the same duration of connection.

c. Means for metering a different initial charge and a different duration charge depending upon the time of the day the call is made. That is to say, calls of equal duration will have a different meter registration depending upon the time of day the call is made, though the calls may have the same origin and destination, the variations depending upon a variable initial charge and also upon a variable duration charge.

d. Means is provided whereby if the call is made to certain groups of lines, no initial or duration charge will be registered.

The foregoing, and other novel objects of the present invention, and the invention itself, will be understood from the following description thereof, together with the accompanying drawings designated Figs. 1 to 10 inclusive.

Reference is made to my co-pending applications Ser. No. 420,018, filed Oct. 27, 1920; Ser. No. 510,016, filed Oct. 24, 1921; Ser. No. 540,779; filed March 3, 1922; Ser. No. 548,165, filed March 30, 1922.

Fig. 1 is an apparatus unit involved in the invention.

Fig. 2 are exchange impulse devices common to a plurality of subscribers' lines and

other equipments, which impulses are subject to control in a secondary manner by apparatus associated with connections made, the said control being in accordance with predetermined charge factors which are in turn controlled by conditions which are variable, depending upon traffic and rate factors.

Fig. 3 shows a first selector of the present invention, in co-operation with a second selector and a connector having access to a called line.

Fig. 4 shows the relation of the first selector in Fig. 3 to other first selectors of its group.

Fig. 5 shows a lineswitch and associated meters of the present invention.

Fig. 6 is a somewhat more detailed illustration of the devices indicated by *a*, *b*, and *c* in Fig. 2.

Fig. 7 is a somewhat more detailed illustration of the devices indicated by *d* and *e* in Fig. 2.

Fig. 8 shows the way the various figures are assembled to display the apparatus of the present invention, the conductor lines running toward the margins which register being understood to be continuations of the same lines.

Fig. 9 shows a portion of Fig. 3, and in addition thereto, a special intermediate selector *J* introduced into an alternative path to selector *SS* of Fig. 3. An equipment element *K* associated in the said alternative path serves to bar connections to pay telephones.

Fig. 10 shows a schematic plan of a wiper and cooperating level of bank contacts of the apparatus unit *A*. The lowermost wiper and bank level is shown, though it is to be understood that it represents each of the levels.

To associate the necessary control apparatus with the meter devices individual to each subscriber's line with the lineswitch thereof (as is shown in my pending application Serial No. 420,018, filed Oct. 27, 1920) entails installing special apparatus more or less costly, for each line, and which requires office space and maintenance in proportion to this quantity.

Relating the apparatus for controlling the meter devices, which are individual to each of the subscribers' lines, with the first selectors reduces the quantity of the said apparatus in the ratio of the number of first selectors to the number of subscribers' lines and individual terminating lineswitches. This in itself effects a saving in equipment containing space and maintenance. How-

ever, the present invention contemplates not only associating the apparatus for controlling the meter devices with the first selectors, but that this apparatus will not be so associated with the first selectors after the necessity thereof has terminated. The present invention also contemplates that the apparatus controlling the first selector shall also be disassociated after the necessity thereof has terminated. So that the present invention thus contemplates a first selector having only such controlling relays and equipment permanently associated with it in carrying out the ends and objects of the present invention as are necessary to maintain the selector seized after the linking has been accomplished, to maintain a correlation of the duration meter devices, and to unseize and restore the selector when the connection is to be terminated.

The present invention would be employed in telephone exchange systems where it is desired to encourage the use of the service at certain periods of the day of generally light traffic and to discourage the use of the service during periods of the day of generally heavy traffic, so as to conduce toward the employment of the installed equipment under a condition of higher service factor than would ensue should the service be induced solely at the whim or inclination of the subscribers, without the incentive for them to adapt the use of the service to economic considerations. To this end not only would the rate charged to the subscriber initially for the establishment of the call be varied throughout the various hours of the day corresponding directly to the general traffic demands, but a supplemental charge, based upon the duration of an established connection will also be varied throughout the various hours of the day corresponding directly to the traffic demands. The two charges, that is, the initial charge and the duration charge, may or may not be varied correspondingly. In addition to the said two basis of charges, the factor of destination will also enter, and again the initial charge and the duration charge will enter into the total charge made for the connection. The charges will be recorded on meter devices so that the initial charge will be represented by one or more units, and the duration charge will be represented by one or more units for each predetermined period of duration, for example, one or two units for each half minute of duration. To this will enter one or more units depending upon what the destination of the call is so that calls to certain lines will involve a higher initial charge, and perhaps, though not necessarily, a higher duration charge than others, all factors being variable according to the time of day the service is established and durated.

65 Charging for telephone service based upon

factors as contemplated herein will appeal to the subscribers as more equitable, and will also serve to reduce the peak demands so that a lesser investment in equipment will suffice to handle the same amount of traffic were not some pecuniary inducement made to the subscribers to adjust their calling in accordance with the most desirable regulation of the traffic from the viewpoint of the operating concern.

75 Referring to Fig. 2, S2 is a solenoid interrupter device having a plunger-arm 201 designed to be drawn upwardly periodically and then automatically released after it has engaged all the contacts co-operative with it. The operating cycle period of the plunger arm 201 is preferably about five seconds. The energizing circuit is from grounded arm 202 to the winding of the solenoid. Arm 202 and arm 203 are attached by an insulating link 205 so that when the plunger-arm 201 rests upon arm 203, arm 202 will rest upon its engaging contact, and when the plunger-arm 201 engages arm 202 on its upward stroke it will disengage arm 202 from its resting contact, deenergizing the solenoid S2 and allowing the plunger-arm 201 to recede by gravity until it re-engages arm 203 and through the insulating link 205 reattracts the arm 202 against its resting contact to re-energize the solenoid to again draw the plunger-arm 201, this cycle of operation continuing indefinitely. The pivoted end of the arm 202 involves mechanical friction so that when the arm 202 is raised from its resting contact it will not retract until the plunger-arm 201 in retracting engages arm 203 and withdraws it. The plunger-arm 201 is also given friction by way of dash-pot action to retard its movement upwardly, so that the plunger-arm will be drawn upwardly at a predetermined slow rate, and released somewhat rapidly, to again be drawn upwardly as before, etc. Bar 206 is grounded while arm 202 is resting on its contact. Plunger-arm 201 makes electrical engagement with the bar 206 with its strokes, and it also engages contacts 208 and 209, so it will appear that each time the plunger-arm 201 is drawn upward the ground on arm 202 will be applied first to contact 208, then to contact 209, and that ground will not be applied to the said contacts incidental to the recession of the plunger-arm 201. Intermediate contacts in pairs 210-211, 212-213, 214-215, 216-217, 218-219, 220-221, are engaged by an insulated conductive member 225 attached to the plunger-arm 201, so designed that as it is drawn over the said pairs of contacts it will short circuit the respective pairs successively, but will not connect contacts of adjacent pairs.

120 Referring to a, b, and c of Figs. 2 and 6, a clock mechanism CK closes a set of contacts 601 to energize the drive magnet 602 every 125

hour so that its pawl 603 will drive sprocket-wheel 604 one twenty-fourth of a revolution at each energization of the drive magnet 602, there being twenty-four teeth in the sprocket-wheel 604. The cams *a*, *b*, and *c* are rigidly connected on a common shaft 605 with the sprocket-wheel 604, so that they will make one revolution every twenty-four hours. The cams are designed so that contact set *a'* will be closed from 6 a. m. to 10 p. m.; the contact set *b'* will be closed from 8 a. m. to 8 p. m., and the contact set *c'* will be closed from 10 a. m. to 12 m., and from 2 p. m. to 5 p. m. Thus, bank contacts 211 and 217 will be grounded between 6 a. m. and 10 p. m.; contacts 213 and 219 will be grounded between 8 a. m. and 8 p. m., and contact 221 will be grounded between 10 a. m. and 12 m., and between 2 p. m. and 5 p. m. Bank contact 215 is permanently grounded. In view of the foregoing, each time plunger-arm 201 is drawn upwardly between the hours of 10 a. m. and 11 a. m., for example, one ground impulse is applied to common conductor 226, four ground impulses to common conductor 227, one ground impulse to common conductor 228, one ground impulse to common conductor 229, and one ground impulse to common conductor 230. And between 1 a. m. and 2 a. m., for example, one ground impulse is applied to common conductor 226, one ground impulse to common conductor 227, none to common conductor 228, none to common conductor 229, and one ground impulse to common conductor 230. It is to be understood that the conductors 226 and 230 will each be grounded one time for each upward stroke of the plunger-arm 201 regardless of the time of day, while the conductors 227, 228, and 229 will not be grounded, or will be grounded, one or more times, depending upon the hour of day when the said plunger-arm is drawn upward.

Referring to *d* and *e* of Figs. 2 and 7, a clock mechanism CK' closes a set of contacts 701 to energize the drive magnet 702 every five seconds, so that its pawl 703 will drive sprocket-wheel 704 one-twelfth of a revolution at each energization of its drive magnet 702, there being twelve teeth in the sprocket-wheel 704. The cams *d* and *e* are rigidly connected on a common shaft 705 with the sprocket-wheel 704, so that they will make one revolution every minute. The cams are designed so that contact set *d'* will be closed one time each minute, and the contact set *e'* will be closed two times each minute.

It will thus appear, in view of the foregoing, that upon the closure of contact set *d'*, relay 231 will actuate and lock to grounded armature 232, preparing a circuit from common conductor 226, armature 233, to the upper winding of relay 234. Upon conductor 226 becoming grounded, incidental to the upward movement of the plunger-arm 201, slow-

releasing relay 234 will energize, causing its lower winding to be locked by way of armature 236, armature 237 to its resting grounded contact, armature 238 preparing a circuit from the upper winding of slow-releasing relay 239 to conductor 230, so that upon the plunger-arm 201 engaging bank contact 209 relay 239 will energize and unlock relay 234, and due to the slow-releasing characteristic of the latter relay, a ground impulse of brief duration will be applied from armature 232, armature 240 to common conductor 242, the object of which will appear presently. In the same manner, upon the closure of contact set *e'*, relay 231' will actuate and lock to grounded armature 232', preparing a circuit from conductor 226, armature 233' to the upper winding of relay 234'. Upon conductor 226 becoming grounded, incidental to the upward movement of the plunger-arm 201, slow-releasing relay 234' will energize, causing its lower winding to be locked by way of armature 236', armature 237' to its resting grounded contact, armature 238' preparing a circuit from the winding of relay 239' to conductor 230 so that upon the plunger-arm 201 engaging bank contact 209, slow-releasing relay 239' will energize and unlock relay 234', and due to the slow-releasing characteristic of the latter relay, a ground impulse of brief duration will be applied from armature 232', armature 240' to common conductor 243.

It will be clear, in view of the foregoing, that regardless of when either relay 231 or 231' is caused to be actuated from the closure of contact set *d'* or *e'*, a ground impulse is stored, as it were, and cannot be applied to conductor 242 or conductor 243, respectively, while the plunger-arm is moving upward over any of the contacts between contact 208 and contact 209. That is to say, an impulse cannot be applied to either of conductors 242 or 243 while an impulse is being applied to conductor 227, 228, or 229, though the closure of said contact set *d'* or *e'* may occur while the plunger-arm 201 is moving upward, and is between the said contacts 208 and 209. The object of this will appear presently.

Referring to Fig. 3, the off-normal spring set SON is adjusted to operate on the second vertical off-normal step of the shaft of first selector C. The off-normal spring set FON is adjusted to operate on the first vertical off-normal step of the said shaft. The off-normal spring set AFN is adjusted to operate only while the said shaft is raised and is at the first off-normal position. The first level of bank contacts is attained at the second vertical off-normal step, rather than at the first vertical off-normal step, as has been common in selectors heretofore. The off-normal spring set FS is designed to be operated from the shaft by the insulated collar *f* upon the wipers carried by the shaft aligning with

a predetermined level or levels. That is, if a certain level of trunks is selected the said off-normal set FS will be operated upon the shaft rotating. The object of the said function will appear, however, it has to do with lines reached through such level upon which no toll charge is to be registered.

The apparatus unit A is shown electrically related to the first selector C, the said A and C, as combined, being an operative unit, whereby the shaft of the selector C can be directly controlled vertically and thence automatically rotated selectively. The drive magnet M is designed so that upon its retraction after being energized it will cause the set of wipers of the apparatus unit A to be driven into engagement with the next set of bank contacts, respectively. Drive magnets operating thus have been used in well known types of lineswitches.

In the system chosen to elucidate the present invention, three sub-groups of three first selectors each (such as C, E, and F), constituting a main group, are employed, each said main group being accessible from a specific group of lineswitches, of perhaps one hundred, terminating an equal number of lines. So that each lineswitch of a certain group of subscribers' lines has common access to the said main group containing nine selectors. Likewise, other groups of subscribers' lines will terminate in corresponding groups of lineswitches at the central office, which latter lineswitches have access to a second group of three sub-groups of three selectors each, there being two subscribers' groups leading to two corresponding lineswitch groups, which two lineswitch groups combined, in turn have access to four selector sub-groups of three selectors each. It will thus appear that the sub-groups of selectors are arranged so that they lap with respect to the main groups of selectors. That is to say, the first three sub-groups of the four sub-groups comprise the first main group of selectors, and the last three sub-groups of the said four sub-groups comprise the second main group of selectors. Under this arrangement if no selector is available in the fourth sub-group to subscribers of the second main group of lineswitches, the calling line will be extended to a selector of the third or second sub-group of selectors which are lapped from the first main group of selectors into the second main group of selectors, so the second main group of selectors contains the second, third, and fourth sub-groups of selectors. The selectors of the sub-groups are connected alternatively as to sub-groups in the banks of the lineswitches of the corresponding main groups of subscribers' lines, and the circuits are so designed that a maximum of one apparatus unit, such as A, can be related with idle selectors of a sub-group. That is to say, if the three selectors of a sub-group are idle, only one of

them can have an apparatus unit associated with it. However, another apparatus unit becomes newly associated with one of the other selectors of the latter said sub-group if the requirement there of the prior associated apparatus unit has not terminated in a connection being established, or if the connection has been established and the apparatus unit has not yet been automatically ejected from connection with it, as will appear presently. Under this condition, if an apparatus unit is respectively associated with one selector of each of the three sub-groups of a main group of selectors, and there is another apparatus unit newly associated with one of the selectors of one of the sub-groups, making two apparatus units for the sub-group, of the latter said main group, in a call which has not been responded to and the initial charge therefor registered, after the said charge is registered and the apparatus unit ejected, as will appear presently, the apparatus unit will not be able to seize a selector of the three sub-groups it is co-operative with, it will rotate selectively off the respective apparatus bank contact sets thereof and stop upon the set of bank contacts of the waiting position provided, there being ten rotary positions in all. Then, if one of the selectors including its co-operating apparatus unit is seized by a lineswitch of a calling line, upon the first directive impulse being applied to the said seized selector causing it to be moved from its first vertical off-normal position, as will appear presently, the apparatus unit (or units) occupying the waiting position will forthwith start automatically functioning selectively, whereupon the next available selector of the concerned sub-group will be seized. Of course the latter said selector seized may have been seized by some other hunting apparatus unit (or units) which had been ejected practically coincidentally, and in that event the apparatus unit (or units) which started hunting from the waiting position will continue and return to the waiting position.

From the foregoing, and as will appear presently, it will be clear that one apparatus unit will be required for each sub-group of selectors, so there will always be three selectors seizable in a main group (the other selectors being barred, as will appear presently), and to this, additional apparatus units as will be required to supply apparatus units for the selectors on connections being established and which have not ejected the concerned apparatus unit therefrom.

While the sub-groups in the exemplified system comprise three selectors, it will be understood that the number may be varied, and in fact, single groups may be employed having any desired number. In the latter case, an auxiliary sub-group, common to a plurality of main groups may be employed to receive an initiated call in the event there is no seized

able selector in the main group. This would be virtually a main group consisting of two sub-groups, however, one said sub-group being a common sub-group with other main groups of selectors.

In a commercial installation the line-switches may have access to twenty-five first selectors, consisting of two sub-groups of ten selectors each, which sub-groups may be also 10 lapped into other main groups, and in addition, a sub-group of five selectors common to a plurality of main groups may be employed to take care of emergency conditions of heavy coincident traffic. In fact, the latter 15 sub-group of five selectors may possibly be complete permanent-unit selectors of well known form.

Under the last above method of employing the present invention, one apparatus unit 20 would be required for each sub-group of ten, and two emergency apparatus units, which will either be in an operating relation to a first selector, or on the waiting position provided. To this will be added the permanent-unit type 25 selectors related to the said sub-group of five, the apparatus units for the said latter sub-group, if selectors of the present invention and apparatus units associated therewith are employed. Thus, but a percentage of the 30 number of selectors employed will be represented by apparatus units.

It will appear that in the illustration the wipers of the apparatus units have access to a main group of nine first selectors, being 35 three sub-groups of three selectors each, and there is one reserve position from which no selectors can be reached. Also, in view of the fact that there is a second main group of selectors similar to the first said main group, 40 of which two of the sub-groups are comprised in the first said main group, there will be a sub-group of three selectors individual to each main group. That is, the first sub-group will be individual to the first main group, and 45 the fourth sub-group will be individual to the second main group.

Referring to the telephones T₅, T₃, and the selector C, (also selectors E and F, shown in part), when combined with apparatus unit A, 50 they belong to the class of A and E, respectively, of the U. S. patent to Newforth, No. 13,901, re-issued April 13, 1915; however, the latter is modified to operate in accordance with the present invention. The lineswitch 55 D, belongs to the class of the lineswitch shown in U. S. patent to Lamb, No. 1,193,160, granted August 1, 1916; however, modified to operate in accordance with the present invention. The meter devices NCM and TM are 60 well known electro-magnet counting devices with index drums corresponding to a plurality of numerical orders. The wipers and co-operating bank contacts of the apparatus unit A are in general similar to the design 65 used in lineswitch D. The connector CON in

Fig. 3 is like connector H in the said cited patent to Newforth, having particular reference to the function of the back-bridge relay 18 of said connector H wherein it reverses the relationship of the leading-in talking conductors with respect to the battery and the ground windings of the front bridge or line relay 16.

The general mechanical form and arrangement of the elements of the automatic telephone apparatus of the present invention having been set forth, the specific operation of the exemplified system will now be described under assumed operative conditions.

Upon the initiation of a call from telephone T₅ by removing the receiver from the switch-hook thereat, a circuit can be traced from the winding of line relay 501, armature 502, line conductor 503, telephone T₅, line conductor 504, armature 506 to grounded resting contact, relay 501 actuating. Assuming that first selector C is seizable by having an apparatus unit associated with it, as drawn, and that, therefore, the shaft of said C has been stepped off-normal and the off-normal contacts are in a condition shown in the drawing because of its being seizable, as will appear presently, no ground will exist on either of bank contacts 510 or 511, and that, therefore, ground will not be communicated to conductor 512 by either wiper 513 or 514. Armature 515 being

normal, the motor magnet M₅ will not be operatively energized, due to the fact that the winding of relay 517 is in series with its winding. However, relay 517 will operatively energize in series with the winding of motor magnet M₅, a circuit being traceable from the winding of motor magnet M₅, armature 520, conductor 521, winding of relay 517, conductor 522 to grounded armature 523. A circuit can now be traced from armature 502, wiper 525, bank contact 526, conductor 527, shunted series winding of electro-polarized relay 301, armature 302, conductor 303, bank contact 101, wiper 102 to the upper winding of line relay 103 and from the lower winding of the latter relay, wiper 104, bank contact 105, conductor 106, armature 304, conductor 305, bank contact 529, wiper 530, armature 506, and through the telephone T₅ to conductor 503, relay 103 energizing. A circuit can now be traced from grounded armature 108, winding of slow-releasing relay 109, the latter relay actuating, a circuit can now be traced from grounded working contact 110, its co-operating armature, conductor 112, armature 113, wiper 114, bank contact 115, conductor 116, resistance 307 to the inside winding of relay 301. The current traversing

the two said windings of relay 301 magnetize differentially and, therefore, its armatures are not operatively attracted at this time, but, as will appear, the current now traversing the outer winding will be changed in direction consequent to a response being attained from

the called line, and under that condition, the armatures on relay 301 will become operatively attracted, the resistance 307 being then short-circuited by armature 308. The latter will increase the current derived through the inner winding of relay 301 to a value which will predominate regardless of the direction of current in the outer winding, so the armatures of relay 301, after operatively attracting, will not retract until ground is removed from conductor 116. At this time a circuit can be traced from grounded contact 118, its co-operating armature, wiper 119, bank contact 120, conductor 121, conductor 532, bank contact 510, wiper 513, conductor 512, armature 523 to the lower winding terminal of relay 517, before armature 523 has retracted, so that no lapse of ground potential will occur to the lower winding terminal of relay 517, the lineswitch D remaining seized.

Upon the party at telephone T₅ manipulating the calling device theret, in accordance with the first digit of the called number (which number is "1111"), relay 103 will deactuate and reactuate one time responsive thereto, whereupon a circuit can be traced from grounded contact 110, upper armature of relay 103, sustained armature 122, winding of slow-releasing relay 123, wiper 124, bank contact 125, conductor 126 to vertical magnet V₃, the vertical magnet operating to set the wipers 312 to 317 (inclusive) into alignment with the first level of bank contacts, reached by two vertical steps, one of which was imparted automatically by the apparatus unit at the time it seized the selector C, as will appear presently. Upon the attraction of armature 127 at the time the vertical magnet V₃ is thus energized from contact 110, a circuit was closed from the winding of shunted relay 128, armature 127, to grounded contact 118, the relay 128 actuating and locking by way of wiper 129, bank contact 130, conductor 131, off-normal spring 318, armature 319 of the rotary magnet R₃, conductor 320, bank contact 132, wiper 133 to grounded armature 134. Upon the retraction of armature 127 following the said impulse to the vertical magnet V₃, a circuit can be traced from grounded contact 118, its co-operating armature, armature 127, armature 135, wiper 136, bank contact 137, conductor 138 to the winding of the rotary magnet R₃, the rotary magnet operating to drive the wipers 312 to 317 into engagement with bank contacts 325 to 330, respectively. If either of bank contacts 325 or 326 constitutes ground potential, because of second selector SS being either busy or its shaft is off-normal, as will appear presently, ground will be communicated to armature 332, conductor 320, armature 319, off-normal spring 318, conductor 131, bank contact 130, wiper 129 to the winding of relay 128, the relay 128 reactuating and establishing a locking circuit from its

armature 134, wiper 133, bank contact 132, conductor 320, armature 319 off-normal spring 318, conductor 131, bank contact 130, wiper 129 to the winding of said relay 128. The before described circuit from grounded working contact 118, its armature, armature 127, is completed through armature 135, wiper 136, bank contact 137, conductor 138, to the winding of the rotary magnet R₃, the rotary magnet operating to drive the shaft carrying wipers 312 to 317 an additional rotary step into engagement with the second set of bank contacts, the locking circuit traced for the relay 128 being opened as before at armature 319. Upon the retraction of armature 319, provided either wiper 312 or 313 receives ground from an engaged bank contact, relay 128 will be caused to be again actuated and locked, as described, this cycle of operations of relay 128 and the rotary magnet R₃ continuing as long as either wiper 312 or 313 receives ground from an engaged bank contact.

Assuming that neither wiper 312 nor 313 encountered ground when they engaged bank contacts 325 and 326, respectively, therefore, when the armature 319 retracted, following the first actuation of the rotary magnet R₃, no energizing circuit was established for relay 128. In this connection it will be noted that ground from contact 118, its co-operating armature, wiper 119, bank contact 120, conductor 121, conductor 532, is maintained on the lower terminal of the winding of seizing relay 335, and as long as armature 134 is attracted or wiper 312 or wiper 313 receives ground from an engaged bank contact, bearing in mind the retracted condition of armature 332, ground will also exist on the upper terminal of the winding of relay 335. That is to say, the relay 335 is thus short circuited. However, upon the relay 128 deactuating, incidental to the armature 319 on the rotary magnet R₃ attracting, the grounded armature 134 retracts and opens the path traced from it to the upper terminal of the winding of relay 335, so if ground is not received through wiper 312 or wiper 313, there will not be ground potential on the upper terminal of the winding of relay 335. Bearing in mind the retracted condition of the armature 319 of the rotary magnet, a circuit can be traced from the winding of relay 128, wiper 129, bank contact 130, conductor 131, off-normal spring 318, armature 319, conductor 320, winding of relay 335, conductor 532, conductor 121, bank contact 120, wiper 119 to grounded working contact 118. Relay 128 is marginally adjusted so that it will not operatively energize included in a circuit path with the winding of relay 335, but the relay 335 will operatively energize under that condition. Therefore, relay 335 operates by way of effecting the seizure of first selector C.

A circuit can now be traced from the bat-

tery winding of the line relay of the second selector SS, conductor 336, bank contact 327, wiper 314, armature 302, shunted series winding of relay 301, conductor 527, bank contact 526, wiper 525, over the traced path including the telephone T5 to wiper 530, bank contact 529, conductor 305, armature 304, wiper 315, bank contact 328, conductor 338 to the ground winding of the line relay of second selector SS, the said line relay actuating and causes its release relay to actuate and apply ground to private conductor 339, in the well known manner, in view of the said cited patent to Newforth. However, in this connection it is to be understood that an addition has been made to the circuits of selector E, of the said cited patent to Newforth, by way of introducing a set of off-normal springs ON3, and which will close and apply ground to auxiliary private conductor 340 upon the first off-normal movement of the shaft thereof, this ground being communicated to bank contact 325, (and its multiples), so that bank contact 325 will constitute ground potential under all off-normal conditions of the second selector SS, the object of which will appear presently.

At the time relay 335 actuated, its armatures 302 and 304 disassociated the windings of relay 103 of the apparatus unit so that relay 109 is caused to deactivate consistent with its slow-releasing characteristic thereafter. Contact 118 thus ceases to apply ground to its co-operative armature. However, no lapse of ground occurs to conductor 121 therefrom, due to the fact, that ground is applied to conductor 339 from the second selector SS before relay 109 deactuates, and thus no lapse of ground potential occurs to wiper 513, so that the lineswitch D is maintained seized.

At the time relay 335 actuates, its armature 342 closes a circuit from grounded bank contact 330, wiper 317, said armature 342, conductor 343, bank contact 140, wiper 141, armature 142 to the winding of relay 143, the latter relay fully operating. In this connection, it is to be understood, relay 143 is marginally adjusted so that it will attract both of its armatures 144 and 145 upon absolute ground being applied to its winding terminal, but that should ground be applied through a resistance having a value equivalent to that of resistance 343, for example, it will be only partially operative, wherein armature 144 will be attracted into engagement with its working contact but that armature 145 will not engage its working contact. The object of relay 143 will appear presently.

Upon the calling party at telephone T5 sending the second digit "1", the second selector SS will operate in the well known manner, and its wipers 345 to 347 will seize bank contacts 348 to 350, extending the connection over conductors 351 to 353, respectively, to the connector CON, the line relay in the con-

70 nector and the release relay therein operating in the well known manner, to apply ground to conductor 351 to maintain the first selector C and the lineswitch D seized before the release relay in second selector SS retracts and removes the ground applied to conductor 339, however, the conductor 339 now receives ground from the connector CON, there having been no lapse of ground thereto.

75 Upon the said calling party sending the last two digits "1-1", the connector CON will be caused to operate, setting its wipers 355 to 357 upon bank contacts 358 to 360, corresponding to telephone T3, and cause the 80 signal bell 361 thereat to be vibrated, in the well known manner, in view of the said cited patent to Newforth. Upon the called party at telephone T3 responding by removing the 85 receiver from the switch-hook thereat, the connector CON will cause the terminals of the front-bridge line relay thereof to be reciprocated with respect to conductors 352 and 353 (in view of the cited patent to Newforth), so that in lieu of the battery winding of the 90 line relay being connected to conductor 352 as normally, it is now connected to conductor 353, and the ground winding is correspondingly transferred from conductor 353 to conductor 352, so the current now traversing the 95 traced circuit including the telephone T5 and the series winding of relay 301 is reversed to that primarily established and maintained up until the said called party responded. Thus, the polarizing and series windings of 100 relay 301 now energizing the core cumulatively, its armatures will operatively attract. That is to say, the relay 301 becomes operatively energized upon the response of the called party. And since the energizing circuit for the winding of relay 335 is now completed from armature 340, the latter said winding, its attracted armature 332, wiper 313 to grounded bank contact 326, the first 105 selector C is also maintained seized. In this connection it will be stated that battery is shown permanently applied to armature 341 through a resistance. This resistance is of a value approximating the value of the winding (as shunted) on relay 128. The relay 110 335 is maintained energized from parallel sources through armature 341 and the winding of relay 128 until the latter is disassociated, as will appear, after which relay 335 is energized through armature 341 solely.

115 Bearing in mind that the solenoid S2, which is common to the main exchange installation, is continually reciprocating its plunger-arm, upon the plunger-arm 201 engaging contact 208 the first time after the relay 301 has been 120 caused to operatively energize, a circuit can be traced from grounded arm 202, bar 206, plunger-arm 201, contact 208, conductor 226, conductor 250, conductor 362, armature 363, right hand springs of set FS, conductor 364, 125 130

bank contact 146, wiper 147, make-before-break spring 149, armature 150 to the winding of slow-releasing relay 151, the latter relay operating and locking to its grounded armature 153 and disconnecting the spring 149 from its resting contact, thereby opening the traced circuit from arm 202.

It will be assumed that the stated call is transpiring at 2:30 p. m., and, therefore, 10 spring sets a' , b' , and c' , are closed, and that, therefore, contacts 211, 213, 215, 217, 219, and 221 constitute ground potential received through the said spring sets in the manner as hereinbefore set forth. Upon the plunger-arm 201 drawing upwardly, and as its insulated conductive member 225 short-circuits the pairs of contacts successively, ground will be first applied from contact 221, contact 220, conductor 227, conductor 251, conductor 252, 20 armature 152, upper armature of relay 151, conductor 154, wiper 155, bank contact 156, conductor 157, bank contact 540, wiper 541 to the winding of the total meter TM, causing it to operate to advance its register-wheel one unit. Upon the member 225 successively short-circuiting bank contacts 219—218, 217—216, and 215—214, it will apply additional ground impulses, making a total of four ground impulses, to conductor 227, and 30 over the traced path to the winding of said total meter TM, the total meter, therefore, advancing its register-wheel a total of four unit spaces, thus far in the assumed call. When the member 225 short-circuits contacts 35 213 and 212, a ground impulse is applied to conductor 228, conductor 253, conductor 254, armature 144, armature 152, upper armature of relay 151, and over the traced path to the winding of the total meter TM, thus advancing its register-wheel an additional unit space, and, upon the member 225 short-circuiting contacts 211 and 210, a ground impulse is applied to conductor 229, conductor 255, conductor 256, armature 145, armature 152, upper armature of relay 151, and over the traced path to the winding of the total meter TM, thus advancing its register-wheel an additional unit space, the total meter, therefore, having advanced its register-wheel a total of 50 six unit spaces thus far in the assumed call. In this connection it will be noted that the energization of the magnets of the meter TM (and also meter NCM) will depend upon the armature 545 of the lineswitch D being attracted. That is, if the lineswitch D is not in a seized state the said meters cannot be operated. This is to prevent the false operation of the meters in case the lineswitch D is resting idly upon the bank contact set corresponding to a selector which is seized by another lineswitch, whereby impulses operating the meters of the seized lineswitch would also operate the meters associated with assumed idle lineswitch D.

Upon the plunger-arm attracting so it ap-

plies the ground received from arm 202 to contact 209, this ground can be traced over conductor 230, conductor 258, armature 158, make-before-break spring 159 to the winding of relay 160. The relay 160 will actuate, whereby a locking circuit can be traced from its winding, spring 159, armature 161, armature 158 to the said grounded contact 209, the said locking circuit enduring only until the plunger-arm is caused to retract due to the mechanical operation whereby arm 202 is caused to open the energizing circuit of the solenoid winding. It will be noted that as the plunger-arm retracts there will be no ground on the bar 206.

At the time relay 160 attracted it unlocked relay 151 at armature 150, and although spring 149 retracts, the relay 151 will not be reenergized due to the fact that conductor 226 is not grounded at this time. Relay 143 will also deactivate due to the attraction of armature 142. Also, incidental to the actuation of relay 160, and before relay 151 deactuates, bearing in mind the slow-releasing characteristic of the latter relay, a circuit can be traced from grounded armature 162, armature 163, armature 164, conductor 165, armature 166 on the motor magnet M to the winding thereof, the motor magnet actuating to drive the wipers of the apparatus unit A into engagement with the next set of bank contacts, respectively, upon the deactuation of the said motor magnet upon its armature 166 interrupting its energizing circuit. At the time the motor magnet M actuates, its armature 167 applies its ground to the winding of slow-releasing relay 168, the latter relay actuating.

Before continuing the description relating to the functioning of the equipment linked in the connection between the calling and called parties, the operation of the apparatus unit will be discussed under variously assumed operative conditions.

It will be noted that when the apparatus unit has its wipers resting upon a set of bank contacts with its relay 168 deactuated, a ground can be traced through its armature 169, wiper 170, bank contact 171, conductor 172 to off-normal spring 365, the latter being disengaged, and, therefore, having no operative effect. However, the conductor 172 and bank contacts corresponding to 171 of other apparatus units in multiple relation thereto will then constitute ground potential, the object of which will appear presently. It will also be noted that due to the attraction of armature 366, a circuit can be traced therefrom through armature 367, conductor 368, bank contact 173, wiper 174 to working contact 175, that is to say, if a selector corresponding to C is in a seized state and a telephonic connection is complete between the calling and called parties, conductor 368 and its multiplied attached bank contacts,

appearing in corresponding relation to the accessible apparatus units, will constitute ground potential. So if the apparatus unit A is hunting, and the relay 168 is therefore actuated when the wiper 174 receives ground from an engaged bank contact corresponding to a selector in a responded-to connection, the ground received therefrom will be communicated through armature 177, conductor 165, armature 166 to the winding of motor magnet M causing it to actuate and advance the wipers from the set of bank contacts corresponding to the latter of said selector, upon the motor magnet M deactuating consequent to its armature 166 interrupting its energizing circuit, whereupon the apparatus unit will be in testing relation to the successive set of bank contacts. It will also appear that if wiper 176 (which also is shown in Fig. 4, the functions of which will be discussed presently) engages a grounded bank contact while relay 168 is actuated, the apparatus unit thus being in a hunting state, a circuit can be traced from said grounded wiper, armature 164, conductor 165, armature 166 to the winding of the motor magnet M, the motor magnet operating by way of advancing the set of wipers off from the set of bank contacts wherein the bank contact engaged by wiper 176 constitutes ground potential. It will further appear that if wiper 178 receives ground from an engaged bank contact, this ground will be communicated through armature 166 to the winding of motor magnet M, causing the wipers to be advanced from the set of bank contacts then engaged to the successive set. And it will also appear that if wiper 170 receives ground from an engaged bank contact while the apparatus unit A is hunting, and, therefore, relay 168 is actuated, this ground will be communicated through armature 169, working contact 175, armature 177, conductor 165, armature 166 to the winding of motor magnet M, the motor magnet operating to advance the wipers to the successive set of bank contacts.

Recapitulating, the apparatus unit A will advance its wipers to a successive set of bank contacts from those its wipers may be resting upon under the following conditions; when wiper 178 receives ground which, as will appear presently, will not only occur when the apparatus unit A has its wipers on a bank contact set corresponding to the resting position but also if said wiper rests on any grounded bank contact; when its relay 160 actuates and unlocks relay 151; when the said unit is hunting and wiper 176 receives ground from an engaged bank contact; when the said unit is hunting and wiper 174 receives ground from an engaged bank contact. Wiper 170 will receive ground whenever it engages a bank contact set wherein an apparatus unit is already resting upon a corresponding set, that is to say, if an apparatus unit in hunting finds an unguarded bank contact set, and, therefore, does not rotate from it, a hunting apparatus unit subsequently testing a corresponding (multiplied) set of bank contacts will not be enabled to stop upon them, but will rotate-off to the successive set, etc. The impulse received through armatures 162 and 163 will only occur when the plunger-arm 201 advances to the end of its stroke and engages bank contact 209, meaning that all of the meter effecting impulses involved in the initial charge have been sent and that, therefore, the apparatus unit is not further required in relation to the selector C.

In this connection it will be noted that at the time relay 151 actuated, its grounded armature 162 applied ground through armature 163, wiper 179, bank contact 180, conductor 181, bank contact 548, wiper 549 to the winding of the magnet of the number-of-calls meter NCM causing it to register one time, the object being to have a record of the total number of completed connections, and in addition thereto, to have a record of the total charges involved therein, which latter, of course, will depend upon the time of day the call is made, the duration thereof, and its destination.

Since the present invention contemplates a duration charge, or charges, it involves operating the meter TM at predetermined periods, which in the assumed call will be one unit registration each half minute. It has been described how the relay 231' is actuated and locked each half minute, preparatory to transmitting its registering impulse after the initial charge impulses have been sent, the novel provision being made to avoid the possibility of coincident impulses being applied to the meter TM. To this end, the relay 231' remains locked until conductor 230 becomes grounded when the plunger-arm advances to contact 209 at the end of its upward stroke, and that relay 234' becomes locked when the plunger-arm 201 engages bank contact 208 at the beginning of its upward stroke and grounds conductor 226, the relay 234' becoming unlocked when the plunger-arm engages contact 209 incidental to relay 239' actuating, followed by the deactuation of relay 231'. An impulse is imparted to conductor 243 through the hereinbefore described functioning of armatures 232' and 240' at the time relay 239' actuates and before relay 234' has permitted its armature 232' to retract due to its slow-releasing characteristic. Bearing in mind that the apparatus unit A is at this time disassociating or has already disassociated from the selector C, a circuit can be traced from conductor 243, conductor 369, bank contact 329, wiper 316, armature 370, conductor 371, bank contact 540, wiper 541 to the winding of the magnet of the meter TM, the said meter advancing a unit step. It will be manifest that due to

the plunger-arm 201 operating more frequently than the contact set *e'* closes, it is most probable that the relay 231' will not have been locked at the time the apparatus unit A disassociated from the selector C, therefore, the impulse applied immediately after its disassociation will not occur as described under the particular condition. However, at such time as contact set *e'* closes subsequently, the relay 231' will actuate and lock, followed by relay 234' actuating and locking when the conductor 226 is grounded, and then applying the ground impulse over the traced path to the magnet of the meter TM. In view of relay 231' unlocking incidental to relay 239' actuating, the relay 231' is in readiness to be again locked when contact set *e'* again closes at the next half minute period, after which relay 234' will be caused to actuate and lock the first time conductor 226 becomes grounded thereafter, followed by the actuation of relay 239' when the conductor 230 becomes grounded, following.

The duration timing devices *d* and *e* are commonly related to the first selector banks of the exchange office, while the initial charging devices *a*, *b* and *c* are commonly related to the first selectors of the exchange office.

Attention is directed to the function of the off-normal spring set FS under the condition of calling a level wherein it will be caused to operate upon the wipers rotating-in. That is, say the third level constitutes a trunk group leading to special intermediate selectors having access to connectors or terminating equipments of lines which may be called without charge. The details of the said special intermediate selectors and equipments associated therewith will be discussed presently.

Upon the off-normal spring set FS operating, wiper 178 will become grounded by way of its engaged bank contact 183, conductor 184, left spring of said set FS, upper armature of relay 335 to wiper 313. The wiper 313 will be grounded when the relay 335 actuates to complete the traced path, receiving its ground from the succeeding selector seized, in the manner as hereinbefore described. Under this condition the motor magnet M will be energized and the wipers of the apparatus unit A will be caused to advance and hunt. The said ground will be applied through the middle spring of the said set FS to the inner winding of relay 301, causing the latter relay to actuate, since the inner winding of relay 301 will operatively attract the armature thereof when applied to direct ground. The said inner winding is now locked to grounded spring 379. The wipers 316 and 317 are now free, since the co-operating bank contacts at the level concerned are unconnected. In this connection, it will be manifest that since the respectively cooperating bank contacts of all positions of

the entire level is concerned, wherein wipers 316 and 317 co-operate with live bank contacts, it will be equivalent to substitute off-normal springs which will be closed to corresponding conductors at the various live levels. Under this latter alternative arrangement the wipers 316 and 317, and the sets of co-operating bank contacts for the live levels may be dispensed with.

It will be noted that where a line is called for which no charge is to be made, the apparatus unit is ejected or caused to hunt forthwith, incidental to the selector seizing, and not delay until after an initial registration is made. Also, that due to the right hand contacts of the off-normal set being open, the traced path from conductor 250 to spring 149 is opened, thus precluding an operation of the meter TM.

While the third level of the first selector C refers to free lines to which a switching charge is not made, and that the said level may have trunks leading to second selectors similar to SS, and the latter to in turn have access to connectors similar to CON, or to connectors which do not cause the direction of current to be reversed back toward the calling party, this arrangement may be varied. In fact the varied arrangement shown in Fig. 9 may be the preferred arrangement under most operative conditions.

Fig. 9 shows a portion of first selector C as shown in Fig. 3, although parts, including the wiring of the lower two pairs of bank contacts engaged by wipers 316 and 317, are left off. However, the second selector SS is shown connected as in Fig. 3, although there is an alternative path to said selector SS by way of the special intermediate selector J and apparatus element K. Under the latter condition, when the selector C seizes the first set of bank contacts of the third level thereof, the connection is extended to selector J, which latter selector is similar to selector SS. The sets of bank contacts of the bank levels of selector J are in corresponding multiple relation with those accessible to selector C. Thus, if the digit "3" is prefixed to any number called through the selector C the selector J will be introduced and the same telephone line reached as if it were not prefixed. However, it has been described how the relay 301 is caused to actuate and lock incidental to the wipers of selector C rotating-in on the third level, so under the condition of the selector J being attained upon sending the first digit "3," the said relay 301 will be then actuated and locked. The next digit called will be "1," which will cause selector SS to be seized by selector J, after which the last three digits "1-1-1" will be sent to operate the selector SS and the connector CON to cause the latter to set its wipers 355 to 357 on bank contacts 358 to 360, respectively, and signal telephone T3, it being assumed that

the right hand portion of Fig. 3 defined by the section line *m*—*n* will be applied to the right of the similarly designated section line in Fig. 9.

- 5 It will be assumed that the telephone T3 is not a telephone to which a call may be made without charge, and in fact the connector CON will determine this by reason of its function of reversing the current supplied 10 to the calling line incidental to the called telephone being responded to. After the wipers 312 to 317 engage bank contacts 384 to 389, respectively, and the second digit "1" has been sent, the paths from wipers 313 to 315 15 have been continued to conductors 339, 336, and 338, respectively, as if the first digit had been "1" in lieu of "3." However, it will appear that the path from wiper 315 is by way of the series winding of shunted electro-polarized relay 908 of equipment element K. 20 Bank contact 905 becoming grounded upon being engaged by wiper 906, (the companion wipers engaging the corresponding companion bank contacts), the inner electro-polarizing winding of relay 908 will become energized. Due to the fact that the conductor 25 338 is the one connected to the ground winding of the line relay winding of the selector SS the two windings of relay 908 will energize differentially, and under that condition 30 will not operatively attract its armature 909. However, upon the connector CON causing the current to be reversed in direction, incidental to the party at telephone T3 responding, the armature 909 will attract and open the ground path including wiper 313, so that 35 the line switch D will unseize and the selectors C and J will restore, followed by connector CON and selector SS.
- 40 Assuming that the connector CON has its reversing armatures blocked so they are inoperative, or that a well known form of connector which does not reverse the current projected back over the calling line is used, or that a connector of the type of connector F in U. S. Patent No. 1,269,245, granted to A. Anderson, June 11, 1918, is employed, and that the line leading to telephone T3 is connected through the tenth or "O" level in 45 lieu of the "1" level, it will appear that the current traversing the series winding of relay 908 will not energize cumulatively with the inner winding thereof, upon a response being attained at telephone T3. Under the latter condition the armature 909 will not be 50 operatively attracted, and, therefore, the connection will not be destroyed, as last before described.
- 55 In view of the last foregoing paragraph 60 it will thus appear that if the selector J is introduced by prefixing the digit "3" and the call is completed to a telephone to which a charge is made, the connection will be destroyed incidental to the called telephone being responded to. Also, if the said call is to
- a telephone to which no charge is to be made, the connection will not be destroyed, it being understood that where no charge is to be made the connector or selector reaching the line called does not cause the current projected 70 toward the calling line to be reversed in direction incidental to obtaining a response on the called line. The arrangement disclosed in Fig. 9 thus provides for free calls over the general trunking system. While the third 75 level has been described as the "free" level, in practice, this may be any level, possibly the first level. Subscribers will know by the digit or letter designation indicative thereof if the line to be called is a "free" line. 80
- Selector C as shown in the drawing, Fig. 3, has its shaft one step off-normal, therefore, the contacts of set FON are open. Were the said selector idle, without an apparatus switch associated therewith, the said off-normal set FON would have its springs closed, and, therefore, its springs 372 would be grounded, and this ground would be communicated to conductor 532, bank contact 510 and its multiples, thus guarding the selector against 85 seizure by a lineswitch. This ground on conductor 532 is communicated over conductor 121 to bank contact 120, the latter to no operative purpose at this juncture. Off-normal set AFN will have its springs normal, that is, the left hand pair of springs will be engaged and the right hand pair will be disengaged. Bearing in mind that E and F represent the shafts of selectors belonging to the sub-group 90 of three containing the selector C, and assuming that they are unrelated to an apparatus unit, and are not in a connection but are at normal, a circuit can be traced from grounded spring 401, spring 402, spring 403, spring 404, conductor 405, spring 373, spring 374, conductor 375, off-normal spring 376, conductor 377, conductor 407 to the winding of relay 408, the latter relay actuating. A path can also be traced from conductor 375 through the lower spring pairs of SON, SON', and 95 SON'' to conductor 407. In view of the last traced circuits it will appear that whenever off-normal sets AFN, AFN', and AFN'' are unoperated, which will mean that the shafts 100 of the selectors C, E, and F are either at normal or above the first off-normal position, and that any one of the off-normal sets SON, SON', and SON'' are unoperated, which will mean that the shafts of the selectors C, E, and F, or any one of them have not stepped above 105 the first off-normal position, the relay 408 will be actuated. For the present it will be assumed, that the shafts of the said selectors C, E, and F are at normal, though in view 110 of the foregoing statements were the shafts of any two of them above the first off-normal position, the circuit traced to the winding of relay 408 would be energized and the said relay actuated. Under the assumed condition, grounded armatures 409 and 410 will 115
- 120
- 125
- 130

apply ground to conductors 411 and 412, respectively, and grounded armature 413 will apply ground to conductor 414, and to bank contact 415 occupying the resting position, 5 there being no selectors corresponding to the resting position. For convenience, the said resting position will be referred to as resting position ten, since it is assumed that there are ten sets of bank contacts in the cycle, nine 10 of which correspond to the three sub-groups of three selectors, referred to hereinbefore. Grounded armature 417 is applied to the free terminal of lamp 418, causing it to glow to indicate the condition, which is, that the 15 group of selectors C, E, and F has no apparatus unit associated with any one of them and is also seizable to an apparatus unit, it being borne in mind, that an apparatus unit may be associated with one of the said 20 selectors and the shaft thereof be above the first off-normal position, perhaps by way of completing a connection which has not yet been answered and the initial charge registered therefor.

25 It will be remembered that under the last stated condition, no selector of the said sub-group is seizable by a lineswitch, due to the fact that it is guarded as set forth, if its shaft is at normal, or if it is seized by a lineswitch. It will be manifest that bank contacts 420, 421, 422, 423, 424, and 425 constitute ground potential, as well as the corresponding multiplied bank contacts engageable to the apparatus unit A by its wipers 178 30 and 176, as indicated, the said wipers being in a position shown in Fig. 1, wiper 178 being also shown in the same position in Fig. 10. The bank contacts designated H are engageable to one of the companion apparatus units 35 to said A which have common access with said A to the second and third sub-groups of selectors and to the fourth sub-group of selectors, so that it has common access with said A to the second and third sub-group of 40 selectors only. It is to be borne in mind that there 45 would be a plurality of apparatus units in access to each of a plurality of main groups constituted of similar sub-groups.

It is to be understood that the selector C 50 will occupy position one, selector E position four, and selector F position seven, the wipers of apparatus unit A being shown as resting upon the set of bank contacts occupying position one. Thus a sub-group of three selectors will also occupy positions two, five, 55 and eight. And a sub-group of three selectors will also occupy positions three, six, and nine. The selectors constituting the sub-groups not shown, but referred to, are to be assumed 60 similar to the sub-group occupying position one consisted of selectors C, E, and F.

In view of conductors 411 and 412 being 65 grounded, and also in view of the statement with reference to wiper 176, wherein if it receives ground from a bank contact, a hunting

apparatus unit will not be enabled to stop thereon; it will appear that the only sub-group of selectors that is not barred against seizure by a hunting apparatus unit is the sub-group occupying bank positions one, 70 four, and seven; all the selectors of the other two sub-groups being barred by reason of relay 408 being actuated because there is no selector in the group occupying the said bank positions one, four, and seven that is seizable 75 to a lineswitch, and it also evidences that there must be a selector in this group nominally seizable because of its shaft being at normal, as otherwise the relay 408 could not actuate, due to the fact that the lower pair 80 of springs of each of all of the off-normal sets SON, SON', and SON'' would then be operated. Under this condition, (relay 408 being actuated), a hunting apparatus unit is constrained to seize one of the selectors of 85 the sub-group occupying the bank positions one, four, or seven, and which are the only selectors of the main group with which apparatus unit A co-operates which are not falsely guarded through the agency of relay 408. 90

Assuming that the apparatus unit A (although it may be any other apparatus unit or units companion to A) is occupying the resting position, and that its wiper 178 is, therefore, resting upon bank contact 415, it 95 will be manifest that since conductor 414 was grounded through the agency of relay 408 coincident with the said relay placing a false guarding condition on the selectors of the said two sub-groups, and in view of the statement wherein if wiper 178 receives ground the motor magnet M will be caused to advance the wipers and hunt, it is clear that the apparatus unit A will forthwith start its 100 hunting operation seeking one of the three 105 selectors of the sub-group containing C, E, and F, and it will stop with its wiper resting upon a bank contact set corresponding to the selector of the said sub-group which does not present a barred condition to the apparatus unit A. 110

In this connection, it will be assumed that the selector C is the one that is seizable, and that, therefore its shaft was at normal, and under which condition it will be remembered 115 the pairs of springs constituting the off-normal set FON will be engaged. Then, upon the apparatus unit A stopping upon the set of bank contacts corresponding to the selector C, a circuit can be traced from the winding 120 of the vertical magnet V3, conductor 172, bank contact 171, wiper 170, armature 169 to its resting grounded contact, the vertical magnet operating to step the shaft up one vertical position, incidentally opening the 125 pairs of springs of the off-normal set FON, and operating the off-normal set AFN, the off-normal set SON not being operatively affected. Ground having thus been removed 130 from spring 372 and bank contact 510 and its

multiples, the said selector C is now subject to seizure by a lineswitch. Due to the operation of off-normal set AFN, the energizing circuit of relay 408 will be opened and the 5 false guarding of the two guarded sub-groups will terminate. The selector C and its co-operating apparatus unit A are now in the condition assumed at the outset, wherein the selector C was directive operated from the 10 calling telephone T5.

Relays 430, 431, and 432 correspond in numerical order to relay 408 with relation to the other three sub-groups of selectors (not shown) and will be caused to actuate under 15 the same conditions as caused relay 408 to actuate, in the foregoing description. However, in view of the fact that the second and third sub-groups are common to both main groups, it will appear that if relay 430 is 20 actuated there is a sub-group of both main groups that requires an apparatus unit, and under that condition, armatures 435 and 436 will apply ground to conductors 414 and 437. Under that condition, should there be an 25 apparatus unit (or units) with its wiper corresponding to 178 resting upon bank contact 415 of the first main group, and an apparatus unit (or units) with its wiper corresponding to 178 resting upon bank contact 440 of 30 the second main group, the said apparatus units will be caused to forthwith advance to the successive set of bank contacts in hunting operation, seeking an idle selector in the second sub-group occupying bank positions 35 two, five, and eight of the first main group, and positions one, four, and seven of the second main group. It is manifest that since grounded armatures 442, 443, and 444 are attracted, conductors 445, 446, and 411 40 are grounded and that, therefore, the selectors of the fourth, first, and third sub-groups are barred against seizure by a hunting apparatus unit; this applying to both main groups of selectors, where a sub-group appears in 45 both said main groups. In the exemplified case, the third sub-group of selectors appears in both said main groups of selectors. It will be manifest that the second sub-group of selectors, which is accessible to the apparatus units of both main groups, is the only 50 sub-group of selectors unguarded falsely, and latter said sub-group is also the one requiring an apparatus unit, as evidenced by the actuation of relay 430. It will appear 55 that ground is now applied from armature 435 to bank contact 415, which will cause a resting apparatus unit of the first main group of selectors to rotate-off and hunt from the corresponding resting bank contact set, 60 should its wiper corresponding to 178 be resting on said contact 415. It will also appear that ground is now applied from armature 436 to bank contact 440 of the second main group, which will cause a resting apparatus 65 unit of the second main group to rotate-off

and hunt from the corresponding resting bank contact set, should its wiper corresponding to 178 be resting on said contact 440. That is to say, when the relay 430 actuates it causes any apparatus units which may be occupying a waiting position of either main group to initiate its hunting operation and seek one of the selectors of the second sub-group of selectors, which has been stated, appears in both main groups, and it will also 70 constrain any other hunting apparatus unit which may have become disassociated from a selector of any sub-group to find a selector of the second sub-group, because it is not able to stop on a selector of any other group. In 80 case no apparatus units are in the waiting position of either main group the relay 430 will continue actuated until an apparatus unit of either main group is disassociated from a cooperating selector, when the said 85 unit will be directed to an idle selector of the second sub-group.

In the same manner as in the last foregoing, if no apparatus unit is associated with a disengaged selector of the third sub-group, 90 and one or more of the selectors thereof has its shaft at normal, and, therefore, relay 431 will be actuated, the selectors which may be seized by an apparatus unit which may be in a resting position or hunting, will be in 95 the third sub-group, which is common to both main groups. And in the same manner, if no apparatus unit is associated with a disengaged selector of the fourth sub-group, and one or more of the selectors thereof has its 100 shaft at normal, and, therefore, relay 432 will be actuated, the selectors which may be seized by an apparatus unit which may be in a resting position or hunting, will be in the fourth sub-group, which appear in the second main 105 group only.

In connection with the latter, it will be noted, the first main group is not concerned, that is conductor 414 is not grounded, but conductor 437 is grounded through armature 110 451. It will be noted here that when any selector of the first sub-group has an apparatus unit associated with it, and the said selector has its shaft standing at the first off-normal position with its off-normal sets FON 115 and AFN operated (the selector may or may not be in seized relation with a lineswitch at the time), the conductor 457 will be grounded. This is due to the right hand springs of the off-normal sets AFN, AFN', and AFN'' 120 being in multiple relation with said conductor 457, and that when a shaft is standing at its first off-normal position a said spring thereof will be grounded. The object of the latter provision is to insure all the selectors of the first sub-group being barred against a hunting apparatus unit if one of the selectors of the said sub-group is in relation to a 125 said unit and the shaft thereof is at normal and the selector is unseized. The latter state- 130

ment is to say that if the selector is seized by a lineswitch, whereby the calling party has not as yet sent the first directive impulse, and, therefore, the shaft will be in the same physical off-normal state as if the selector had not been seized, the conductor 457 would not then be grounded due to the fact that the ground applied to right hand spring of the off-normal set AFN, for example, is received through grounded armature 169, armature 182, wiper 174, bank contact 173, conductor 368 and spring 382, the said path being opened at armature 182 when the selector is seized due to relay 109 actuating. Under this condition, while the conductor 457 becomes grounded upon the selector being seized by an apparatus unit, and thereby bars any idle selectors remaining in the sub-group containing it, upon the selector being seized by a lineswitch, the conductor 457 becomes ungrounded and the idle selectors of the said sub-group are then subject to seizure by a hunting apparatus unit.

In a like manner springs 460 and 461 are caused to be grounded through conductors 368' and 368'' over a corresponding path in an engaged selector as was traced from the corresponding conductor 368, to the grounded contact upon which armature 169 normally rests. It will now be manifest, that if a selector is seized by a lineswitch, and the calling party does not forthwith start the directive impulses, the idle selectors of the concerned sub-group will not be barred falsely against a hunting apparatus unit, so that a said apparatus unit can seize and adapt the latter seized selector for seizure by a lineswitch, notwithstanding the said selector last seized has not been operated directly by the calling party.

With reference to relays 408, 430, 431, and 432, it will be noted that they each derive energizing current through chained armatures of the preceding relays. This is to insure that one only of the said relays can be operated at any time; the relays predominating from the left. Otherwise, a condition may be wherein all sub-groups of a main group could become falsely barred, as by the relays 430 and 431 actuating coincidentally, for example. It will be noted in this connection if relay 432 becomes actuated, conductor 414 will not become grounded, so an apparatus unit of the first main group which may occupy the resting position will not be caused to hunt.

With reference to the bank contacts shown in G and H, it will be understood that the right hand contact adapted to be engaged by wiper 176 is dead, and that the first nine contacts adapted to be engaged by wiper 178 appertain to conductors of nine accessible first selectors, while the tenth bank contact only refers to the waiting position. It will be manifest that a plurality of waiting bank positions may be provided for waiting posi-

tions by tying them in multiple. The latter bank positions, of course, would not be available for co-operating selectors. In this connection, it will appear, a greater number than nine selectors may be in access to the apparatus units and the lineswitches, in fact, in commercial installations the number would usually be twenty-five or more, the sub-groups each having five or more selectors, in lieu of three as described in the exemplified system.

Going back to the condition of the circuits wherein the party at telephone T5 was in telephonic relation with the party at telephone T3, bearing in mind the relation of conductor 243 to the said connection for recording duration charges. It will be assumed that the party at telephone T5 replaces the receiver thereat on the switchhook to terminate the service. The connector CON will operate, in the well known manner, responsive thereto and remove the ground from conductors 351, 339, and 532, which will deenergize relays 517 and 335, the relay 301 being maintained energized through off-normal spring 379. Upon the deactuation of relay 335, a circuit can be traced from the winding of release magnet Re3, armature 367 to grounded armature 366, the release magnet operating to restore the shaft of selector C to normal, incidentally disengaging spring 379 when the shaft leaves the second off-normal position in restoring, thereby causing relay 301 to deactivate. Upon the shaft arriving at normal, ground will be applied through spring 372 to bank contact 510, and its multiples, to guard the selector C against seizure, grounded armature 366 maintaining a ground upon conductor 380 to bank contact 511, and its multiples, consistent with the slow-releasing characteristic of its relay 301, so that the bank contact 511 will constitute ground potential, at least until the ground is re-applied to bank contact 510 through spring 372. That is to say, at no time since the selector C was first seized by the lineswitch D has both bank contacts 510 and 511 been free from ground simultaneously. The object of the novel arrangement whereby the lineswitch D has an auxiliary private wiper and co-operating contacts is to insure that when a lapse of ground potential occurs to conductor 532, causing the private bank contact 510 to become ungrounded and the selector C is caused to restore, as set forth in the last foregoing, the said selector is not unguarded with respect to other lineswitches which may be hunting or in a seizing state with reference to the said selector C. Under such condition the relay of the lineswitch concerned corresponding to 517 will be in a deactuated state, and, therefore, the wipers corresponding to 513 and 514 will be tied. In view of the fact that bank contact 511 and its multiples will constitute ground potential received from

armature 366 until after the shaft of selector C has restored to normal the said selector cannot be seized by a lineswitch while the shaft is restoring. Moreover, when the shaft has 5 restored, and before the armature 366 retracts, the conductor 532 becomes grounded through spring 372 and thus guards the selector C against seizure until the latter said ground is removed. The latter can only 10 occur when the shaft is stepped off-normal incidental to the selector being seized by an apparatus unit A, for example, as has been described.

In view of the last foregoing, it will now 15 be clear that the off-normal spring set ON3 on the second selector SS will maintain ground potential on bank contact 325 and its multiples, so that if a selector tests the contacts corresponding to SS, after conductor 20 339 becomes ungrounded, as described, and before the shaft of selector SS has had time to restore to normal, the wiper of the testing selector corresponding to 312 (tied to its wiper corresponding to 313 through the upper retracted armature of its seizing relay) 25 will cause the testing selector to rotate-off. Selector SS being a complete unit type selector, the seizing of it under the stated condition would not usually vitiate a call, though 30 should the second selector SS be of the same general type as selector C herein, or of the exact type of selector B as shown in my pending application Serial No. 510,016, filed October 24, 1921, for example, it is essential, 35 for the reason that under the said condition no apparatus unit is associated with it, and the call would be vitiated if seized under the condition. The last foregoing described condition is the equivalent to the condition described 40 wherein the lineswitch D is barred from seizing the selector C until an apparatus unit has become associated with it, the testing circuit as relates to its test wiper and auxiliary test wiper and their respective co-operating bank contacts being generally similar in said D and C. The operation and purpose of the off-normal spring set ON9 is the 45 same as that of the said off-normal set ON3.

Had the described connection through selector SS been attained through the second level of selector C in lieu of the first level thereof, the resistance 343 would then have been included in the energizing circuit of relay 143, and under that condition its armature 50 144 only would be operatively attracted, and, therefore, the ground impulse applied from bank contact 210 would not be effective in the initial charge, the assumption being that the trunks leading from the second level of selector C extend in the direction of lines to 55 which a lower initial charge is made. That is, the initial charge in the present instance is five units in lieu of six in the case where the trunks of the first level of selector C were concerned. Also, since conductor 243, which

concerns contact set e' does not lead to the said first level, but that conductor 242 which concerns contact set d', does lead to the said second level over conductor 381, connecting to bank contacts co-operative with wiper 316, a different duration charge will be recorded for an equal period at the same hour. The contact set d' closes one time each minute, causing relay 231 to actuate and lock to armature 232, in the manner as before described, and in view of the descriptions with relation to relays 231', 234', 239', and conductor 243, having in mind the corresponding arrangement with reference to relays 231, 234, 239, and conductor 242, it will now be clear that each 70 minute the conductor 242 becomes grounded, so that if the relay 301 is actuated the total meter TM will be caused to be advanced one unit each minute, regardless of whether an apparatus unit is associated with the selector. That is, as long as the connection endures after the response is obtained and relay 301 actuates, the meter TM will be operated periodically, thus recording a duration charge. However, when the selector has seized a bank 80 contact set on the second level this period is one minute, in lieu of one-half minute as occurs when the first level is concerned, as has been set forth. So in the present instance the initial charge is five units and the duration 85 charge is one unit each minute, rather than an initial charge of six units and one unit each half minute where the first level is concerned.

It will appear, in light of the foregoing, that if conductor 381 is disassociated, no duration charge will be recorded. Also, if the resistance 343 is disassociated, no extra registration of one unit will be introduced as a trunking charge initially. That is, if the bank contacts engageable to wipers 316 and 317 are dispensed with no extra trunking charge or duration charge will be introduced, and it is, therefore, manifest that certain levels may, therefore, have trunks leading in the direction of lines wherein either or both the extra one or two units by way of an initial charge is omitted and the duration charge of one unit per half-minute, or of one unit per minute period, is omitted. The third level, which concerns lines called without charge 105 would be thus arranged, as well as other levels where limited charges are made.

It will be manifest that if the call transpires at 2 a. m., there will be an initial charge of but one unit, due to the sets a', b', and c' being open, a ground impulse being possible from contact 215 only.

Attention is called to contact sets d'' and e'', which are effective only during the period of from 10 a. m. to 12 m., and from 2 p. m. until 6 p. m. due to the ground therefor being open at other times. Under this condition the duration charge will be at a double rate, that is, the duration registrations will be made at periods one-half as long as at other times. 125 130

So, by the latter arrangement the duration charge may be varied so that at periods of generally heavy traffic the charges will be higher than at other periods. This general plan of varying the duration charge may, of course, be varied throughout wide limits without departing from the scope of the present invention.

While the circuits have been specifically described as being associated with an apparatus unit, it is manifest that the circuits shown in the apparatus unit may be related permanently with the selector C, if desired. Other changes, either by way of an amplification or a curtailment, of the system shown and described by way of illustration, may be made in adapting the invention to the varied commercial requirements, without avoiding the present invention, in view of the subjoined claims.

I claim:—

1. In a telephone system, a call meter specific to a calling line, switch mechanism for establishing talking connections, a common means for operating the meter to record the charge for a call, means whereby said common means can only operate one meter at a time, means automatically operative responsive to the completion of recording the charge on said meter for disconnecting said common means from the meter, and means for then connecting said common means with another call meter in lieu of first said meter and for operating last said meter while the first said call continues.

2. In a telephone system, a call meter specific to a calling line, switch mechanism for establishing connections, a common means for operating the meter to record a charge for a call, means whereby said common means can only operate one meter at a time, means automatically operative responsive to the completion of recording the charge on said meter for disconnecting said common means from the meter, means for then connecting said common means with another call meter in lieu of first said meter and for operating last said meter while the first call continues, and means for again operating first said meter to record an additional charge for first said call after said disconnection and before the call is terminated.

3. A telephone system including a selective switch having common driving apparatus and control relays therefor temporarily associated therewith during the driving period, a meter device, impulse mechanism associated with the control relays for operating said meter device, means for disassociating the control relays and said impulse mechanism after the selective switch has been driven in the direction of a specific class of lines and the said toll impulse mechanism has operated, but leaving the selective switch operated, and other means made automatically

operative responsive to the said selective switch being alternatively driven in the direction of a specific class of lines for forthwith disassociating the control relays and said impulse mechanism, but leaving the selective switch operated.

4. In a telephone system, a main group of selectors made up of a plurality of sub-groups of said selectors, a plurality of sets of common drive relays for temporary association with any selector of the main group during the driving period, but leaving the driven selector operated, co-operating antecedent selective switches, means in a driven said selector controlled from a connected line for restoring it, automatically applied means for co-operating a said set of drive relays with a selector of a said sub-group and barring other said sets of drive relays from the said sub-group if the concerned selector of the sub-group is unseized by a said antecedent switch, and means for unbarring the unseized selectors of the sub-group to the said sets of drive relays consequent upon the first drive impulse being applied to the selector having the drive relays cooperated therewith.

5. In a telephone system, a main group of selectors made up of a plurality of sub-groups of said selectors, a plurality of sets of drive relays for temporary association with any selector of the main group during the driving period, but leaving the driven selector operated, co-operating antecedent selective switches, means in a driven said selector controlled from a connected line for restoring it, automatically applied means for co-operating a said set of drive relays with a selector of a said sub-group and barring other said sets of drive relays from the said sub-group if the concerned selector of the sub-group is unseized by a said antecedent switch, means for holding idle said sets of drive relays, and means for unbarring the unseized selectors of the sub-group to the said sets of drive relays consequent upon the first drive impulse being applied to the selector having the drive relays cooperated therewith and for causing the idle said sets of drive relays held to initiate their hunting movement to seize an unbarred selector of the sub-group unbarred.

6. In a telephone system, a calling line, two classes of called lines, common selective switches for interlinking a connection from the calling line to a called one of any said called lines, an alternative route from the calling line to the line called involving a like said connection and an auxiliary link, and means whereby a talking connection is prevented from being completed by way of only one of the said routes to one of the said classes.

7. In a telephone system, a calling line, two classes of called lines, common selective switches for interlinking a connection from

- the calling line to a called one of any said called lines, an alternative route from a calling to the called lines involving a like said connection and an auxiliary link, and means whereby a talking connection is prevented from being completed by way of one of the said routes to only one of the said classes but may be completed to lines of the other class.
8. In a telephone system, a calling line, free and toll called lines, common selective apparatus for interlinking a talking connection from the calling line to a called one of said lines, a meter device on the calling line, an alternative route between the calling and a said toll called line involving a like said connection and an auxiliary link, means for operating the meter from the toll line called, but not from the free line called, and means whereby if a toll line is called by way of the alternative route a talking connection is prevented from being completed.
9. In a telephone system, a plurality of selective switches having component parts thereof common thereto, a calling line, a called line, a toll assessing device companion to the calling line, means controlled from the calling line for directly operating a said selective switch by way of extending a connection from the calling line towards the called line, means for completing the connection to the called line, means for operating the toll assessing device consequent to a response on the called line, means operated consequent to the operation of the last said means for disconnecting the said parts common to the switches from the operated said switch, and means for thereafter periodically operating the toll assessing device during the period of maintaining the established connection.
10. In a telephone system, a calling line, a selective switch having common control relays therefor temporarily associated therewith during the driving period, a meter device for said calling line, meter operating mechanism associated with the control relays, means for disassociating the control relays and the said meter operating mechanism after the selective switch has been driven in the direction of a specific class of lines and the said toll operating mechanism has operated, but leaving the selective switch operated, and other means made automatically operative responsive to the said selective switch being alternatively driven in the direction of a specific class of lines for forthwith disconnecting the control relays and said meter operating mechanism, but leaving the selective switch operated.
11. In a telephone system, calling and called lines, trunk lines each requiring a specific toll charge, means for extending a connection from a calling to a called line including one of said trunk lines, means for automatically initially variably charging the calling subscriber according to the trunk line over which
- the call is extended consequent to a response from the called line regardless of how long the responded state is maintained, and automatically applied means for then charging the calling subscriber at predetermined intervals, the latter said charges not being a function of the initial charge regardless of when the call ensues.
12. In a telephone system, calling and called lines, means for extending connections between the calling and called lines, a toll meter companion to the calling line, a meter control device for operating the meter a plurality of times as a single toll assessment for establishing the connection, and means for thereafter periodically operating the meter a plurality of times, each said periodic plurality of operations of the meter constituting the minimum toll assessment for any part of the corresponding duration period for the specific call.
13. In a telephone system, calling and called lines, means for extending connections between the calling and called line, a timing device, a toll meter companion to the calling line, a meter control device for operating the meter a plurality of times as a single toll assessment for establishing the connection, and means including the timing device for thereafter periodically operating the meter a variable plurality of times, each said periodic plurality of operations of the meter constituting the minimum toll assessment for any part of the corresponding duration period for the specific call.
14. In a telephone system, calling and called lines, means for extending connections between the calling and called line, a timing device, a toll meter companion to the calling line, a meter control device for operating the meter a plurality of times as a single toll assessment for establishing the connection, and means including the timing device for thereafter periodically operating the meter a variable plurality of times, each said periodic plurality of operations of the meter constituting the minimum toll assessment for any part of the corresponding duration period for the specific call.
15. In a telephone system, in which are means for setting up connections automatically between calling and called lines, the calling line having a meter, and in which the calls so set up require varying toll charges, a mechanism for operating the meter a varying number of times in accordance with the charge required, and a timing device operable to assess additional varying charges upon the calling subscriber's meter at predetermined intervals during the holding of the connection after a response on the called line has occurred, the said variations depending upon the time of day through which the connection is held.
16. In a telephone system, in which are

- means for setting up connections automatically between calling and called lines, the calling line having a meter, and in which the calls so set up require varying toll charges, 5 a mechanism for operating the meter a varying number of times in accordance with the charge required, and a timing device operable to assess additional varying charges upon the calling subscriber's meter at predetermined 10 intervals during the holding of the connection after a response on the called line has occurred, the latter said variation depending upon the time of day through which the connection is held.
- 15 17. In a telephone system, in which means are provided for setting up connections automatically between calling and called lines, the calling line having a meter, and in which the calls so set up require varying charges as 20 toll, a timing device, mechanism for operating the meter a varying number of times to assess a toll charge dependent upon the time of day the call occurs, and means to assess additional varying toll charges upon the calling subscriber's meter at predetermined 25 intervals during the conversation period, the latter said variations and the intervals being separately controlled by the timing device.
- 30 18. In a telephone system, in which means are provided for setting up connections automatically between calling and called lines, the calling line having a toll meter, a meter operating mechanism, the meter for operating 35 a plurality of times as an assessment for establishing a connection and for operating a plurality of times as one assessment for a predetermined unit period of maintained connection, means for automatically varying 40 the said assessments independently dependent upon the time of day.
19. In a telephone system, in which means are provided for setting up connections automatically between calling and called lines, the calling line having a toll meter, a meter operating mechanism, the meter for operating 45 a plurality of times as an assessment for establishing a connection regardless of how long the connection is maintained, and for 50 thereafter operating a plurality of times as one assessment for a predetermined minimum unit period of maintained connection, and automatically applied means for varying the latter said assessment independently of the 55 former assessment.
20. In a telephone system, in which means are provided for setting up connections automatically between calling and called lines, the calling line having a toll meter, a first 60 meter operating mechanism connected for operating only the said meter to assess a first charge for establishing a said connection regardless of the duration thereof, a second meter operating mechanism connected 65 for operating the said meter to assess a sec-
- ond toll charge of different amount from said first charge for each predetermined minimum unit period of maintained connection, and means whereby the said first meter operating mechanism can be disconnected from the concerned connection and employed in a new connection while leaving the said second operating mechanism operatively connected for the duration of first said connection without altering the connection of the said second meter operating mechanism.
21. In a telephone system, in which means are provided for setting up connections between calling and called lines, each calling line having a toll meter, a first meter operating mechanism for operating the meter to assess a charge for establishing a said connection, a second meter operating mechanism for operating the meter to assess a duration charge for each predetermined unit period of maintained connection, the said meter operating mechanism being common to a plurality of simultaneously ensuing connections established consecutively, and means for preventing a duration charge being assessed for any specific connection until after a predetermined period elapses after the said establishing charge is assessed for the concerned connection.
22. In a telephone system, in which means are provided for setting up connections between calling and called lines, the calling line having a toll meter, a first meter operating mechanism for operating the meter a plurality of times to assess a charge for establishing a said connection regardless of its duration, and a second meter operating mechanism for operating the meter to assess a duration charge for each unit period of maintained connection, the establishing charge 105 and the duration charge for each period being unrelated.
23. In a telephone system, calling and called lines, means for establishing a connection between said calling and called lines, a toll meter companion to the calling line for recording toll assessments, a meter operating mechanism, means in the meter operating mechanism for assessing a specific toll charge for the establishment of the connection regardless of its duration, the said specific charge being variable with relation to the time of day the call is made, means in the meter operating mechanism for assessing a specific toll charge for each specific unit period the completed connection is maintained, the value of the latter said assessments being independent of the value of the assessment for the establishment of the connection.
24. In a telephone system, calling and called lines, means for establishing a connection between said calling and called lines, a toll meter companion to the calling line for recording toll assessments, a meter operat-

ing mechanism, means in the meter operating mechanism for assessing a specific toll charge for the establishment of the connection regardless of its duration, the said specific charge being variable with relation to the time of day the call is made, means in the meter operating mechanism for assessing a specific toll charge for each specific unit period the completed connection is maintained, the value of the latter said assessments varying from period to period in accordance with the time of day the call is maintained.

25. In a telephone system, calling and called lines, means for establishing a connection between said calling and called lines, a toll meter companion to the calling line for recording toll assessments, a meter operating mechanism, means in the latter said mechanism for assessing a specific toll charge for the establishment of the connection regardless of its duration, but variable in accordance with the path of the call through the telephone system and the time of day the connection is established, means in the meter operating mechanism for further assessing a toll charge for each specific period the connection is maintained, and means for independently altering the length of the said periods.

26. In a telephone system, calling and called lines, means for establishing a connection between said calling and called lines, a toll meter companion to the calling line for recording toll assessments, a meter operating mechanism, means in the latter said mechanism for assessing a specific toll charge for the establishment of the connection regardless of its duration, but variable in accordance with the path of the call through the telephone system and the time of day the connection is established, means in the meter operating mechanism for further assessing a toll charge for each specific period the connection is maintained, and means for independently altering the length of the said periods and the said toll assessment for a said period.

27. In a telephone system, calling and called lines, means for establishing a connection between said calling and called lines, a toll meter companion to the calling line for recording toll assessments, a meter operating mechanism, means in the meter operating mechanism for assessing a duration charge for the maintaining of the connection, the said assessments being automatically effective to the meter for each specific period of duration of the connection, and means in the meter operating mechanism for varying the duration charge for each said period and for also varying the length of the period in accordance with the time of day.

28. In an automatic telephone system, subscriber's lines, automatic switches for estab-

lishing a talking connection from one of said lines to another, a toll device associated with a calling one of said lines, a plurality of controlling devices any one of which may be employed to variably control the operation of said toll device, means automatically responsive to the closing of the hook switch of the called subscriber in responding for operating the said toll device and for then disconnecting the concerned controlling device from the connection for the duration of the call regardless of how long the call is maintained, and means operable variably with the time of day the response occurs for determining what said variable operation the toll device shall make.

29. In a telephone system, a calling line, free and toll called lines, a switch for completing a talking connection from the calling line to the said toll line and the said free called line alternatively, a supplemental common link for inclusion in the connection from the calling line to the switch at will, and means in the said link whereby if the link is employed in a call to a free line a connection can be completed and whereby if the call involves the link wherein a toll line is called the completion of the connection will be barred.

30. In a telephone system, a calling line, free and toll called lines, a switch for completing a talking connection from the calling line to the respective said toll line and the said free called line alternatively, a supplemental common link for inclusion in the connection from the calling line to the switch at will, and means in the said link controlled from the switch whereby if the link is employed in a call to a free line a connection can be completed and whereby if the call involves the link wherein a toll line is called the completion of the connection will be barred.

31. In a telephone system, a calling line free and toll called lines, a common switch for completing a connection from the calling to the respective said called lines over two routes from the calling line alternatively at will, a link for use in only one of said alternative routes, and means whereby if the toll line is called employing said one route for the connection, talk over the connection will be barred.

32. In a telephone system, a calling line, free and toll called lines, a common switch for completing connection from the calling line to either a said free called line or a said toll called line, an auxiliary link for tandem connection in the call at will during the extending of the call to a called free line or alternatively to a called toll line, and means whereby talking service over the connection to only a called toll line will be barred if the connection to the line called includes the auxiliary link.

33. In a telephone system, a calling line, free and toll called lines, a common switch for

completing connection from the calling line to either a said free called line or a said toll called line, an auxiliary link for tandem connection in the call at will during the extending of the call to a called free line or alternatively to a called toll line, and means whereby if the extended connection to the called toll line includes the auxiliary link in tandem the connection to the line called will be destroyed consequent upon a response on the called line if the last said called line is a toll line.

34. In a telephone system, a calling line, free and toll called lines, a meter device on the calling line, means for completing a connection from the calling line to the said called lines over alternative trunk routes, means to disable the meter device consequent to progressing the call in the direction of the free line wherein the said progression is also in the direction of the toll line, means for completing the said progression to the free line and maintaining the connection after a response is obtained thereon, means for alternatively completing the said progression to the toll line, and means for destroying the connection consequent upon a response on the toll line.

35. In a telephone system, a calling line, free and toll called lines, a meter device on the calling line, means for completing a connection from the calling line to the said called lines over alternative trunk routes, means to disable the meter device consequent to progressing the call in the direction of the free line wherein the said progression is also in the direction of the toll line, means for completing the said progression to the free line and maintaining the connection after a response is obtained thereon, means for alternatively completing the said progression to the toll line, and means for barring a talking connection from being completed with the subscriber on the toll line.

36. In a telephone system, a calling line, a selective switch having common component operating relays therefor temporarily exclusively connected therewith, a meter device for said calling line, meter operating mechanism associated with the operating relays, means for disconnecting the operating relays and the said meter operating mechanism from said switch after said switch has been driven in the direction of a specific class of lines and the said toll operating mechanism has operated, but leaving the said switch operated, and other means made automatically operative responsive to the said selective switch being alternatively driven in the direction of a specific class of lines for thereupon disconnecting the operating relays and said meter operating mechanism from said switch, but leaving the selective switch operated.

37. In a telephone system, in which are means for setting up connections automatically between calling and called lines, the calling

line having a meter, and in which the calls so set up between specific calling and specific called lines require varying toll charges, a mechanism for operating the meter a varying number of times in accordance with the charge required, and a timing device operable to assess additional varying charges upon the calling subscriber's meter at predetermined intervals during the holding of the connection after a response on the called line has occurred, the said variations depending upon the time of day through which the connection is held.

38. In a telephone system, in which are means for setting up connections automatically between calling and called lines, the calling line having a meter, and in which the calls so set up between specific calling and specific called lines require varying toll charges, a mechanism for operating the meter a varying number of times in accordance with the charge required, and a timing device operable to assess additional varying charges upon the calling subscriber's meter at predetermined intervals during the holding of the connection after a response on the called line has occurred, the first said varying toll charges depending upon the time of day the response occurs.

39. In a telephone system, in which are means for setting up connections automatically between calling and called lines, the calling line having a meter, and in which the calls so set up between specific calling and specific called lines require varying toll charges, a mechanism for operating the meter a varying number of times in accordance with the charge required, and a timing device operable to assess additional varying charges upon the calling subscriber's meter at predetermined intervals during the holding of the connection after a response on the called line has occurred, the latter said variations depending upon the time of day through which the connection is held.

40. In a telephone system, in which means are provided for setting up connections automatically between calling and called lines, the calling line having a toll meter, a meter operating mechanism, the meter for operating a plurality of times as an assessment for establishing a connection regardless of how long the connection is maintained and for thereafter operating a plurality of times as one minimum assessment for each minimum unit period of maintained connection, automatically applied means for varying the said assessments dependent upon the time of day.

41. In a telephone system, in which means are provided for setting up connections automatically between calling and called lines, the calling line having a toll meter, a meter operating mechanism, the meter for operating a plurality of times as an assessment for establishing a connection regardless of how

long the connection is maintained and for thereafter operating a plurality of times as one minimum assessment for each minimum unit period of maintained connection, automatically applied means for varying the last said assessments.

42. In a telephone system, in which means are provided for setting up connections automatically between calling and called lines, the

- 10 calling line having a toll meter, a meter operating mechanism, the meter for operating a plurality of times as an assessment for establishing a connection regardless of how long the connection is maintained and for there-
- 15 after operating a plurality of times as one minimum assessment for each minimum unit period of maintained connection, automatically applied means for varying first said assessment.

20 43. In a telephone system, a call meter specific to a calling line, switch mechanism for establishing talking connections, a common relay first operative after the completion of the call for operating the meter to record a

- 25 charge for the call regardless of its duration, and means automatically operative responsive to the completion of recording said charge for disconnecting said relay and for rendering the relay subject to use with another meter in lieu of first said meter while the first call continues.

44. In a telephone system, a call meter specific to a calling line, switch mechanism for establishing talking connections, a com-

- 35 mon relay first operative after the completion of the call for operating the meter to record a charge for the call regardless of its duration, means automatically operative responsive to the completion of recording said
- 40 charge for disconnecting said relay and for rendering the relay subject to use with another meter in lieu of first said meter while the first call continues, and means for reoperating first said call meter to assess an additional charge for the call.

45. In a telephone system, a call meter specific to a calling line, switch mechanism for establishing talking connections, a common relay first operative after the completion of

- 50 the call for operating the meter to record a charge for the call regardless of its duration, means automatically operative responsive to the completion of recording said charge for disconnecting said relay and for rendering the relay subject to use with another meter in lieu of first said meter while the first call continues, and means for periodically reoperating the call meter first operated until the call is terminated.

55 46. In a telephone system, a call meter specific to a calling line, switch mechanism for establishing talking connections, a common relay first operative after the completion of the call for operating the meter to record a charge for the call regardless of its duration,

means automatically operative responsive to the completion of recording said charge for disconnecting said relay and for rendering the relay subject to use with another meter in lieu of first said meter while the first call continues, means for periodically reoperating first said call meter until the first said call is terminated, and means for varying said re-operations responsive to the changes in the time of day so as to assess different additional charges for the same call duration periods of equal length.

47. In a telephone system, a call meter specific to a calling line, selective switches for establishing talking connections, a common relay mechanism first operative after the completion of the call for operating the meter to record a charge for the call, means automatically operative responsive to the completion of recording the charge for disconnecting said mechanism and for rendering said mechanism subject to operating a call meter of another calling line in lieu of first said meter while first said call continues.

48. In an automatic telephone system, a plurality of calling lines, a plurality of called lines, selective switches for establishing talking connections, a call meter specific to each calling line, a common relay mechanism first operative after the connection is completed for operating only one said meter at a time to record a charge for a call from a said calling to a said called line, means automatically operative responsive to a response on the called line for causing said mechanism to operate the meter of only the connected calling line, means automatically operative responsive to the operation of the relay mechanism after operating said meter for thereupon disconnecting said mechanism from the connection and for then rendering said mechanism subject to operating a said call meter of another said calling line while first said call continues.

49. In a telephone system, a calling line, called lines of two classes, a switch for completing connection from the calling line to the respective called lines at will, a branched leading-in trunk to the switch, means for effecting connection from the calling line to the switch over one or the other said branch at will, means for then operating the switch into connection with a called line of one or the other said classes at will, and means controlled over the line called if of a specific one said class for destroying the connection consequent to a response thereon dependent upon a specific said branch being employed in effecting the connection.

50. In a telephone system, a calling line, called lines of two classes, a switch for completing connection from the calling line to the respective called lines at will, a branched leading-in trunk to the switch, means for effecting connection from the calling line to

the switch over one or the other said branch at will, means for then operating the switch into connection with a called line of one or the other said classes at will, and means whereby depending upon what said branch is employed which will determine if a talking connection is possible or is precluded to a specific one of said classes of called lines.

51. In an automatic telephone system, a 10-calling line, called lines of two classes, an automatic switch for completing connections to said called lines, a branched leading-in trunk for the switch, and means whereby depending upon what branch is employed in effecting connection from said calling line to the switch will determine if a talking connection from the connected calling line is possible to both said classes or only to one of said classes.

52. In a telephone system in which are 20 means for setting up connections between a calling and a called line, a call meter, a means controlled over the called line for operating the meter to assess a specific charge for a 25 call regardless of any control thereafter occurring upon the called line, means for assessing an additional charge for each prede-

termined period of maintained call, and means for varying the total charge for a specific plurality of said periods depending upon the time of day said call durates.

53. In an automatic telephone system, calling lines, called lines, automatic switching mechanism for connecting a calling line to a called line, a toll assessing device on the respective calling lines, a mechanism common to said calling lines for operating the toll assessing device of a calling line, means responsive to initiating a call on the calling line for operatively associating the said common mechanism therewith, means operated responsive to control over a connected called line for disconnecting the said common mechanism, and means dependent upon an operation on the calling line while the call is maintained initiated for disconnecting said common switch mechanism before a called line is connected with without thereafter abandoning the initiated call.

In witness whereof, I hereunto subscribe my name this 28th day of November, A. D. 1921.

HERBERT M. FRIENDLY.
